UNITED STATES PATENT OFFICE.

CARL HINRICHES, OF FRANKFORT-ON-THE-MAIN, GERMANY.

REFRIGERATOR OR COOLER.

No. 909,597.

Specification of Letters Patent.

Patented Jan. 12, 1909.

Application filed November 15, 1906. Serial No. 343,602.

To all whom it may concern:

Be it known that I, CARL HINRICHES, a subject of the German Emperor, and a resident of Frankfort-on-the-Main, Germany, have invented certain new and useful Improvements in Refrigerators or Coolers, of which the following is a specification.

The object of my invention is to provide improved refrigerators, or coolers.

According to my invention the refrigerating chamber is provided, in its upper part, with an ice container, or with ice containers, which may be arranged side by side, or one behind another, or both side by side and one behind another. Under this ice container, or each of these ice containers, is arranged a roof-shaped device whose sides slope downwards towards the sides of the refrigerating chamber and have openings in them for the passage of air and vapors from beneath, the construction preferably consisting of slots arranged after the manner of louvers. The bottom of the ice container, or of each ice container, corresponds in shape with the roof below it and is arranged as close to it as is permissible. By this means the cooling surface for the air passing into the cooling chamber, and therefore the cooling effect, is greatly increased, the air passing through the ice container, or containers, being cooled to a very low temperature and descending, on account of its increased specific gravity, passes over the roof, or roofs, and acts by suction on the warmer air and vapors which are under the roof, or roofs, and draws the said warmer air and vapors through openings in the roof, or roofs. The cooled air falling from the ice container, or ice containers, and the roof, or roofs, exerts pressure on any vitiated, or spent, air in the remainder of the cooling chamber, and expels the said vitiated, or spent, air through a slit, or slits, at the back, or both at the back and front, walls of the cooling chamber, which slit, or slits, conducts, or conduct, the said air therefrom to the ice container, or ice containers, to be again cooled. As a consequence of this arrangement, the air circulates briskly and uninterruptedly through the cooling chamber, thereby removing va-

pors and bad odors and the cooling space is uniformly cooled.

The invention is applicable to coolers, refrigerators, and the like, generally.

In the accompanying drawings, Figures 1 and 2 show a cooling installation constructed in accordance with this invention with cooling arrangements side by side, Fig. 1 being a partial longitudinal section and Fig. 2 a transverse section on the line A—A of Fig. 1. Figs. 3 to 7 illustrate arrangements in accordance with this invention applied to a refrigerator, or ice safe, Fig. 3 being a longitudinal section at right angles to Fig. 4, and Fig. 4 being a cross section at right angle to, and on the line C—C of Fig. 3. Fig. 5 shows, partly in section, a modification adapted for exhibiting purposes. Fig. 6 is a vertical section on the line D—D of Fig. 5, and Fig. 7 is a back view.

In the cooling chamber 1 (Figs. 1 and 2) are arranged side by side several ice containers 2 completely closed against access of external air. Each of these ice containers is closed at the lower part by a bottom 3 consisting of perforated sheet metal, or wire-netting, or the equivalent, so that the ice water forming can escape from the containers 2. Under each ice container, and completely separated therefrom, is a roof 4 consisting of angularly arranged pieces one above the other and having a space between them after the manner of louvers. The bottoms 3 of the ice containers 2 are of a shape corresponding to the general figure of the roofs 4 and are situated as near to the said roofs as is practicable. The air cooled in the ice containers 2 passes through the bottoms 3 and is very cold and meets first the surfaces composing the roofs 4. On account of its increased specific gravity, the air descends rapidly over the oblique faces of the roofs and sucks the air and vapors that have accumulated directly under the roofs 4 through the spaces between the component parts of the roofs and carries the said air and vapors downward, in a cooled, or condensed, state to the bottom of the cooling chamber. The cooling air thus moves downwards on both sides of the roofs 4. A fur-

ther part of the hotter, or spent, air of the cooling chamber 1 passes through slots 6 provided in the bottom of the rear wall 5 of the cooling chamber into passages, or trunks 7 provided between the rear wall 5 and the wall of the building, and extending from the bottom part of the cooling chamber 1 to near the upper part of the ice chamber. In the said trunks, the hotter, or spent, air is compressed by the colder air that moves downward. From the trunks 7 the air passes through slots 8 (which connect the ice containers 2 with the passages, or trunks, 7) into the ice containers 2 wherein it is cooled 10 to issue again through the bottoms 3 and take part in the cooling of the cooling chamber 1.

In order that the amount of cooling air leaving, and passing to, the cooling chamber 20 shall be as large as possible, the ice containers 2 are provided at their front, and side, faces with air outlets 9. From these outlets the air issues and descends together with the air issuing from the bottoms 3 of the ice 25 containers 2. The rear sides of the ice containers 2 extend as far as the rear wall 5 of the cooling chamber and are not provided with outlet openings so that air cannot escape through the rear walls of the ice containers. In order to remove the water that falls from the ice containers 2 onto the roofs 4, there are arranged on each of the lower edges of the roofs, gutters 10 leading to outlet pipes. In order that the escape of the 35 water may take place as quickly as possible so that the air does not become laden with moisture that might settle in the cooling chamber, the two gutters 10 are arranged so as to slope towards the outlet pipes and the 40 components of the roofs are preferably made of corrugated plate thereby to provide small channels on said roofs running from the top thereof to its lower edge, and gathering the ice-water and conducting the same speedily 45 into the gutter.

To assist as much as possible the removal of the hotter, or spent, air from the cooling chamber, suction pipes 11 are distributed in the cooling chamber, one end of the said 50 pipes opening into the said chamber and the other end opening into the trunks 7. When these suction pipes are of great length, they are preferably provided with suction nozzles opening into the cooling chamber. Hotter, or spent, air from the cooling chamber is drawn through the suction pipe 11 by the 55 currents of air rising in the trunks 7. The charging of the ice containers 2 is effected through doors 12 provided in the front walls 60 of the cooling chamber, or the charging may be effected through openings arranged in the top over the ice containers, or the charging may be effected through side doors 13 (Fig. 1). In cooling chambers of great

depth, the ice containers may be arranged 65 not only side by side, but also one behind the other. In this case the trunks, or passages 7, connecting the lower part of the cooling chamber with the ice containers are preferably arranged both in the front and 70 rear walls of the cooling chamber.

Important advantages which the hereinbefore described arrangement possesses over those hitherto known are that a downward current of air passes over the articles placed 75 in the cooling chamber and that moisture cannot deposit on, or disagreeable odor be acquired by, the said articles, which can thus be kept for a long time in a fresh and good condition.

In the ice safe illustrated by Figs. 3 and 4, there is provided an ice-container like one of those in the arrangement shown in Figs. 1 and 2, closed to the access of external air and arranged at the upper part of the safe 85 14, and provided with a perforated, or reticulated, bottom 3 and roof 4 as hereinbefore described, the air cooled in the ice container 2 escaping through the said bottom and meeting the roof 4 and passing down it 90 and sucking, through the spaces in the roof, the air and vapors that have accumulated under the said roof, the said air and vapors being cooled and condensed and passing downwards into the cooling chamber, as in 95 the arrangement shown in Figs. 1 and 2. Below both of the lower edges of the roof 4, the side walls 15 project inwards, whereby the current of the cooled air is deflected from its downward course sidewise of the 100 cooling chamber, and directed towards the center thereof. The air which descends is diverted inwards at these places so that the cold air traverses the middle portion of the 105 cooling chamber. A further part of the 110 hotter, or spent, air in the cooling chamber passes, as in the arrangement shown in Figs. 1 and 2, through a slot 6 in the rear wall near its lower end, into a passage, or trunk, 7, wherein it is compressed by the descending 115 colder air and then raised through the slot 8 and trunk 7 into the ice container wherein it is cooled to again pass through the bottom 3 and take part in the cooling of the cooling chamber. Also, as in the arrangement shown in Figs. 1 and 2, in order that the quantity of air passing from the ice container 2 to the cooling chamber may be as large as possible, the said ice container is provided at its front and side walls with 120 air outlet openings 9. The air escapes from these, sinks along the side surfaces 15 and along the front wall of the cooling chamber with the air issuing from the ice tank 2. Also, as in the arrangement shown in Figs. 1 and 2, the rear side of the ice container 2 extends as far as the rear wall of the cooling chamber and is not provided with any 125

outlet openings, so that air cannot issue from the ice container at its rear side, and to lead away water that trickles down from the ice container 2 onto the roof 4, gutters 5 10 connected to outlet pipes 16 are provided. To collect the water, there is provided, below the cooling chamber, a separate receptacle 17 fitted with a cock to empty it.

The cooling arrangement shown in Figs. 10 5, 6 and 7 is generally constructed like that shown in Figs. 3 and 4. It is provided with shelves 18 for the reception of the various articles to be cooled, and the chamber 14 is, at the front part, closed by doors 19, which 15 can be turned down on horizontal hinges. At the side and rear parts, the chamber is closed by fixed walls. In the arrangement shown, the rear face of the chamber 14 is constituted by a double wall, part of which 20 is of glass. The other walls can be constructed in the same manner if desired. By thus making one, or more, of these sides of glass, or by providing the sides with panes of glass, the cooling device thus constructed 25 can be used as cases for exhibiting the articles contained therein.

Having now particularly described and ascertained the nature of my said invention and in what manner the same is to be performed, I declare that what I claim is:—

1. In a refrigerator, the combination with a casing having a provision chamber, and an ice-chamber above the provision chamber, of means forming a passageway between the 35 ice and provision chambers, the inlet to said passage from the ice chamber being at a higher level than the outlet of the passage and the outlet from the provision chamber into said passage being directed towards 40 the outlet of the passage and closed toward the connection between said passage and the ice-chamber, said passage being adapted to direct the cooling medium downward and sidewise of the provision chamber.

2. In a refrigerator, the combination with a casing having therein a provision chamber, of a roof for said provision chamber, an ice-box arranged above said roof and having its bottom adjacent thereto and forming a passage therewith, the bottom of the ice-box being apertured to form an inlet to said passage from the ice-box at a higher level than the outlet of the passage, the outlet of said passage communicating with the provision 50 chamber and adapted to direct the cooling medium from the passage downward and sidewise of said chamber, and the roof of the provision chamber having therethrough a passage that connects said chamber with 55 said passage between the ice-box and provision chamber and has its discharge end directed toward the outlet of the last said passage and not opening toward the aperture in the bottom of the ice-box.

3. In a refrigerator, the combination with 65 a casing having therein a provision chamber, of a sloping roof for said provision chamber, an ice-box arranged above said roof and having its bottom adjacent thereto and forming a passage therewith, the bottom of the ice- 70 box being apertured to establish communication between the ice-chamber and passage and the outlet of said passage being arranged to deliver the cooling medium downward and sidewise of the provision chamber, the roof 75 of the latter having therein a duct extending from the provision chamber to said passage and having its discharge end directed toward the outlet of the latter and closed toward the passage from the ice-box. 80

4. In a refrigerator, the combination with a casing having therein a provision chamber, and an ice chamber arranged above the provision chamber, of a sloping roof for the provision chamber forming a passage between 85 said chambers and communicating with and adapted to direct the cooling medium downwards and sidewise of said provision chamber, said roof being composed of louver-boards providing ducts connecting the provision chamber and passage and opening toward the outlet of the latter. 90

5. In a refrigerator, the combination with a casing having therein a provision chamber, of a sloping roof for said chamber, an ice 95 box arranged above said roof and having a perforated bottom adjacent thereto and forming a passage therewith, adapted to direct the cooling medium downward and sidewise of the provision chamber, said roof 100 being composed of louver-boards providing ducts connecting the provision chamber and passage and opening toward the outlet of the latter.

6. In a refrigerator, the combination with 105 a casing having a provision chamber, and an ice-chamber in its upper part, of a roof for said provision chamber forming a passage between the ice and provision chambers, the bottom of the ice chamber being apertured 110 to connect said ice-chamber and passage, the inlet to said passage from the ice-chamber being disposed at a higher level than the outlet of the passage, said roof having therein a passage extending from the provision chamber to said passage between the ice and provision chambers and having its outlet directed towards the outlet of the last said passage and closed towards the ice-box, and a trunk connecting the lower part of the provision chamber with the upper part of the 115 ice-chamber. 120

7. In a refrigerator, the combination with a casing having a provision chamber, and an ice-chamber in its upper part, of a roof for 125 said provision chamber forming a passage between and communicating with both said chambers, the inlet to said passage from the

ice-chamber being disposed at a higher level than the outlet of the passage, and the connection between the provision chamber and said passage, through said roof, having its outlet directed towards the outlet of the passage and closed toward the ice-box, a trunk connecting the lower part of the provision chamber with the upper part of the ice-chamber, and a pipe connecting said trunk

at an intermediate point in its length with 10 the provision chamber.

In testimony whereof I have signed my name to this specification in the presence of two subscribing witnesses.

CARL HINRICH.
